COOLING DEVICE BY VAPORIZATION FOR
INTERNAL-COMBUSTION ENGINES

Georges Levesque du Rostu, Paris, France, assignor to Societe Anonyme Andre Citroen, Paris, France

Application July 20, 1945, Serial No. 606,227
In France July 20, 1942Section 1, Public Law 690, August 8, 1946
Patent expires July 20, 1962

7 Claims. (CL. 123—174)

1

The present invention relates to cooling devices for internal combustion engines in which a part of the cooling fluid is vaporized, condensed and brought back into the cooling circuit, whilst the other part remains in a liquid state in said circuit; this invention more particularly covers the applications of this device to automobile motors.

For the convenience of the description, the cooling fluid shall be designated as water.

The cooling devices by vaporization now in use generally exhibit the following drawbacks:

1. The apparatus in which the separation of the water and the steam is carried out (vaporizer or separator) is heavy and cumbersome.

2. When the vehicle stops, after prolonged running, a more or less important loss of steam or water occurs.

In order to obviate these drawbacks, in accordance with the present invention, a single radiator is used fulfilling at the same time the following functions:

Separation of the water and the steam.

Condensation of the steam during the normal running of the motor.

Condensation of the steam—produced when stopping the motor after prolonged running—without any mechanical ventilation device of the radiator core.

This radiator comprises three parts:

(a) An upper box containing the water and steam separating system.

(b) Radiator tubes with fins.

(c) A lower box containing permanently a water reserve at a lower temperature than that of boiling water under atmospheric pressure (100° C.), with a view to condensing the steam produced when the vehicle stops.

The accompanying drawing shows diagrammatically, merely in an indicative manner, a form of embodiment of the present invention.

Fig. 1 shows the whole of the installation for cooling a motor by vaporization in which the new radiator is used.

Fig. 2 shows the profile in cross-section of this radiator.

Fig. 3 is a sectional front-view of the same radiator.

Fig. 4 is a variant of the lower box of the radiator.

In Fig. 1, the cooling water circuit of the motor which proceeds along the path indicated by the arrows, comprises the suction pipe 2 connected with the upper box or chamber 3 of the radiator

2

6, the centrifugal pump 1, the outlet pipe 4 of the motor 5.

The steam circuit is entirely located within the radiator 6 in accordance with the arrangement hereinafter to be described.

The circuit for the return of the water condensate, comprises the suction pipe 8 connected with the lower box or water condensate reservoir 9 of the radiator 6, the pump 7 and the delivery pipe

10 connected with box 3.

The radiator core 6 is supposed, in Fig. 1, to be mechanically cooled by the fan 11 actuated by the motor.

The upper box or chamber 3 (Figs. 2 and 3) 15 comprises a connecting pipe 4a at the upper end, to which is connected the pipe 4 and a connecting pipe 2a, at the lower end, to which is connected the pipe 2. The first connection pipe communicates with a hermetic tank 12 provided in the box 3 and comprising a number of openings 13 at its lower side. The two baffles 14 and 15 are arranged along the length of the box 3. This box further comprises the filling orifice 23, the connecting pipe for the water condensate pipe 10 25 and a partition wall 25 closing the water tank 26.

The vertical tubes 16 of the radiator core 6 are in communication, on the one hand, at their upper end, with the steam chamber 17 formed on the side of the tank 26 in box 3, and, on the 30 other hand, at their lower end, with the chamber 18 for the condensate. The latter communicates only with the two connecting pipes 19 connected to the bubbling pipe 20, comprising a number of holes 21.

35 The chamber 18 and the pipes 19 and 20 form the inner members of the lower box or water condensate reservoir 9. This box furthermore comprises the connecting pipe 8a for the suction pipe 8 of the pump 7, the pipe 22 for letting out 40 the air (air vent) as well as an emptying pipe 24 located at the lowest level.

In Fig. 4, which illustrates a variant of the box 9, the vertical tubes 16 of the radiator are not connected to a chamber 18 as shown in Figs. 2 45 and 3, but are merely extended to the proximity of the lower part of the box 9 that is to say under the water level within said box or water condensate reservoir 9.

The apparatus operates as follows:

50 At the moment when the motor is started, assuming the latter to be cold, the water stands at a certain level in the tank 26 of the box 3; its circulation takes place in the direction shown by the arrows, that is, under the action of the centrifugal pump 1, the water from pipe 4 enters

under pressure the capacity 12, passes through the openings 13 and is then drawn off from the box 3 by the suction of pump 1.

The temperature of this water progressively but rapidly rises. The air contained in the pipings and the various members is expelled through the pipes 16, 19 and 20 and finally into the box 9, whence it is let out by the air vent 22.

When the temperature of the water reaches 100° C., the internal pressure of the box 3 is maintained at substantially the same value as that of the surrounding atmosphere, in view of the small losses of pressure in the steam circuit; steam is evolved by the expansion of the water under pressure through the openings 13 and it draws along with it a certain amount of water. The separation of the water and the steam is carried out by the circulation of the fluid through the baffles 14 and 15, and, finally, it is dry saturated steam which collects at the upper part of the steam chamber 17. Condensation takes place during the passage through the tubes 16 of the radiator core, the condensate flowing down by gravity.

If a first run is being made, the originally empty box 9 fills gradually with water of condensation up to the level of the suction pipe 8. This water of condensation passes through the holes 21 of the horizontal pipe 20. This level of water of condensation remains constant during the whole of the operation, the output of the pump 1 being larger than the flow of water of condensation, and this level is finally maintained even during stoppage.

The radiator core is so determined that the water of condensation is maintained, in the most unfavorable case for cooling, at a temperature distinctly lower than 100° C. Under these conditions, when the motor stops suddenly, as there is no longer any cause for the ventilation of the core, live steam is discharged from the cooling circuit, passes without any appreciable condensation through the vertical tubes 16 of the radiator core, then bubbles in the warm water contained in 9, through the holes 21. This warm water undergoes a correlative rise in temperature, depending on the one hand, on its mass, and on the other hand, on its initial temperature. These two factors have been chosen so that, in the most unfavorable case, the final temperature remains however below 100° C. Under these conditions, there can be no cause for the loss of steam through the air vent 22.

After a renewed start, the temperature of the water of condensation decreases and becomes stabilized rapidly to the initial lower value. This water of condensation, drawn in at 8, is discharged by the pump 1 into the pipe 10 where it is recirculated in the circuit of the pump 1.

In the modification shown in Fig. 4, the bubbling of the steam, in case of stoppage, is directly carried out at the end of the tubes 16 which depend into the water of condensation.

The capacity of the lower box 9 of the radiator has been made sufficient so that any accidental drawing off of water, due for example to a sudden stoppage, is transferred to said box without the air vent opening 22 being drowned. The return to the normal level in box 9 occurs rapidly within the first moments which follow a new start.

What I claim as my invention and desire to secure by Letters Patent is:

1. Cooling device for internal combustion engines by evaporation at atmospheric pressure,

comprising a water condensate reservoir, an upper chamber, vertical tubes communicating at their lower ends with said water condensate reservoir and at their upper ends with said upper chamber, said upper chamber being divided by baffles into a steam chamber arranged directly above said tubes, and a water chamber, this latter communicating by means of connecting pipes respectively with the water circuit of the motor and with said water condensate reservoir, a hermetic tank within said water chamber, said hermetic tank communicating with a connecting pipe for the water from the motor and being provided with openings communicating with said water chamber.

2. Cooling device for internal combustion engines by evaporation at atmospheric pressure, comprising a water condensate reservoir, an upper chamber, vertical tubes opening at their lower ends below the water level within said water condensate reservoir and at their upper ends with said upper chamber, said upper chamber being divided by baffles into a steam chamber arranged directly above said tubes, and a water chamber, this latter communicating by means of connecting pipes leading respectively to the water circuit of the motor and from said water condensate reservoir, the connecting branch with said water condensate reservoir being arranged at a determined level of the water within said water condensate reservoir, a hermetic tank within said water chamber, said hermetic tank communicating with a connecting pipe for the water from the motor and being provided with openings communicating with said water chamber.

3. Cooling device for internal combustion engines by evaporation at atmospheric pressure comprising a water condensate reservoir, an upper chamber, baffles dividing said upper chamber into a steam chamber and a water chamber, vertical tubes communicating at their lower ends with said water condensate reservoir and at their upper ends with said steam chamber, a pipe leading water from said water chamber to the water circuit of the motor, a pump on this pipe, a hermetic tank within said water chamber, a pipe leading water from the water circuit of the motor to said hermetic tank, openings establishing a communication between said water chamber and said hermetic tank, a pipe-line connecting said water chamber and said water condensate reservoir, and a pump on this pipe-line.

4. Cooling device for internal combustion engines by evaporation at atmospheric pressure comprising a water condensate reservoir divided into an upper part and a lower part, said upper and lower parts being superposed, an upper chamber divided by baffles into a steam chamber and a water chamber, vertical tubes communicating at their lower ends with said upper part of said water condensate reservoir and at their upper ends with said steam chamber, connecting pipes leading from the bottom of said upper part of said water condensate reservoir and opening below the water level within said lower part of said water condensate reservoir, a pipe-line connecting said lower part of said water condensate reservoir and said water chamber, a pump on this pipe-line, a pipe for water from said water chamber to the water circuit of the motor, a pump on this pipe, a hermetic tank within said water chamber, a pipe leading water from the water circuit of the motor to said hermetic tank, and openings providing a communication between said hermetic tank and said water chamber.

5. A cooling device as defined in claim 3 where-
in said water condensate reservoir is provided
with an air vent and an emptying pipe.

6. A cooling device as defined in claim 4 where-
in said lower part of said water condensate res-
ervoir is provided with an air vent and an emp-
tying pipe.

7. A cooling device as defined in claim 4 where-
in said connecting pipes leading from the bottom
of said upper part of said water condensate res-
ervoir and opening below the water level within
said lower part of said water condensate res-
ervoir comprise vertical pipes connected to a hori-
zontal bubbling pipe which is arranged below the

water level within said lower part of said water
condensate reservoir and is provided with a num-
ber of holes.
